UNITED STATES PATENT OFFICE.

DELBERT WHEELER, OF SIOUX FALLS, SOUTH DAKOTA.

ROAD MACHINE.

Application filed August 11, 1927. Serial No. 212,291.

My invention relates to road machines, and has for its object to provide primarily a road maintaining and surfacing machine, which may be used upon roads having either 5 soft surfaces, such as dirt, clay, sand and the like, or those having semi-hard surfaces, such as gravel, old macadam, etc.

My invention involves the use of a cutter of the rotary type and it is my purpose to 10 provide a machine in which a single rotary cutter combines the function of scraping and cutting with that of conveying the dirt to fill the low spots and to bring the surface to the proper grade.

15 I am aware that the rotary screw has before been used in connection with road machinery. In most cases, a rotating screw has been employed to convey material laterally and has comprised ordinarily a single blade 20 screw, or a screw having a relatively low pitch so that the scraping action of the blade against the road bed will be largely in a direction transverse to that in which the machine is moving. In most cases, such rotary 25 conveyors are used in connection with straight blades or other devices for loosening the material from the road bed and acting principally as conveyors.

In fulfilling my object of providing a cutter 30 to act both as a conveyor and cutter, I utilize a plurality of helical blades which have pitch angles of relatively large magnitude, (somewhere approximately 45°). I find that such a cutter accomplishes several 35 desirable objects. In the first place, and most important, each blade is presented to the road at an angle of approximately 45° to the line of travel to the machine, and when rotated oppositely to the direction of rotation of the wheels of the machine, will obtain 40 a cross between a shear and a sliced cut. At the same time, the rotation of the cutter will throw the material both in a forward and a lateral direction so as to reduce the 45 tendency of the material to resist forward movement of the cutter and to convey the material to the low spots where it may be deposited. Another result that is had is the 50 production of a practically straight cut in a direction transverse of the roadway without the necessity of revolving the cutter at a very high rate of speed, that is, the surface of the road bed will be left smooth and free from ridges running longitudinally of the 55 roadway.

An object of my invention has been to combine the features of moving material forwardly and obtaining a shearing cut without ridging effects with that of the lateral conveying of material so as to more efficiently 60 fill all those spots in such a manner as to obtain the highest efficiency in each function.

With these and other objects in view my invention consists in the construction, arrangement and combination of the various 65 parts of my device, whereby the objects contemplated are attained, as hereinafter more fully set forth, pointed out in my claims, and illustrated in the accompanying drawings, in which:

Fig. 1 is a plan view of a road machine embodying my invention.

Fig. 2 is a right side elevation of the same.

Fig. 3 is a transverse, sectional view of the same, taken on the line 3—3 of Fig. 2.

Fig. 4 is a detail, sectional view taken on the line 4—4 of Fig. 1.

Fig. 5 is a detail, sectional view taken transversely through the cutter.

Fig. 6 is a detail, sectional view taken on the line 6—6 of Fig. 1.

Fig. 7 is a detail, sectional view taken on the line 7—7 of Fig. 3.

In the accompanying drawings, I have shown in a general way the frame of a road 85 machine which may comprise the longitudinal members 10, the front cross members 11, the intermediate cross member 12 and the rear cross member 13, all connected by gusset plates 14 or the like.

An inner frame is formed between the cross members 12 and 13 and the auxiliary, longitudinal frame members 15, which are secured thereto and extend therebetween in positions spaced inwardly from the longitudinal members 10. In the spaces thus formed, the cutter suspending mechanism, which will later be described, is received.

The frame is supported upon rearward and forward travel wheels 16 and 17, respectively.

100 The cutter is of the rotary type, as has already been stated, and comprises a cylinder 18, mounted upon a shaft 19 by means of spiders or the like 20 at the ends of the cylinder. The cutting blades 21 are L shaped in 105 cross section, the shorter arms 22 of the blades being secured to the cylinder 18 by riveting, bolting, or the like.

Although I have shown eight of the cutter 110 blades, a lesser or greater number may be

employed. It will be understood, however, that one feature of my invention necessitates the use of a plurality of blades and a number less than four will probably not be successful in accomplishing the result which I seek to obtain. As many more than eight blades may be used, up to a point where the close proximity of the blades will interfere with the bite which any one blade can procure against the surface of a road bed. For this reason, the limits between which my invention can be most successfully practiced will be from six to twelve blades. In employment of eight blades, as shown in Fig. 5, the blades are set at an angle of approximately forty-five degrees to the axis of the cylinder 18 and will be spaced apart substantially as shown in Fig. 3.

It may now be noted that a cross-section 20 through a cut produced by moving the cutter in a direction transverse to its axis will be very nearly straight, the ridges between the blades being comparatively shallow. It may be noted further that by rotation of the cutter, 25 in a direction reverse to that of the rotation of the wheels, through an eighth of a revolution, the position of one blade will shift to that of the adjacent blade and consequently if the cutter is revolving at a rate of one revolution 30 per second, any particular point in the path of the cutter blades will be scraped by eight of the blades each second. Assuming the cutter to be geared directly to a small gasoline engine having a normal speed of approximately 35 600 R. P. M. and geared down so as to turn about one-fourth as fast as the engine, it will receive power at the rate of approximately 150 R. P. M. or two and one-half revolutions per second. At this rate, a particular point in the roadway will be subjected 40 to approximately twenty blade contacts per second.

The normal speed of a road machine in a forward direction might be taken as approximately two feet per second. Thus in a distance of two feet forward travel, a particular line parallel to the direction of travel will have been crossed by some blade twenty times and in a distance of approximately an 50 inch and a half of forward travel, one of the blades will have moved so as to take the position of the adjacent blade.

It will be seen from this that the cutter may be rotated at a very reasonable rate of 55 speed and yet the road machine moved ahead at the normal rate without producing longitudinal ridges in the road from the curved edges of the blades. The surface left by the cutter will be absolutely straight in 60 cross-section.

The inclination of the blades is such that there will be a tendency to carry the material, which is scraped from the road bed, in a lateral direction.

65 It may be noted at this point, however, that

it is undesirable to exaggerate this lateral conveying function of the cutter. It will be remembered at this point that the primary purpose of my invention is to provide a road-maintaining machine and that I do not wish to transport material beyond the inner end of the cutter any more than will result of necessity. In road maintenance, the grade of the road bed has been definitely established and the only cutting that is necessary is for the purpose of reducing the slight elevations which have formed and depositing the material scraped from these elevations into the adjacent depressions. In the ordinary gravel road, there is a tendency for the road bed to assume what is known as the "wash board" effect, in which parallel ridges are formed, extending transversely of the road. The cause of this condition probably proceeds from the fact that the springs in most cars are tuned so as to respond to similar vibration periods and the consequent regular jumping of the wheels tends to increase the depth of the regularly produced depressions.

It will now be seen that in order to most efficiently reduce these transverse ridges, the proper method is to deposit the material from one ridge in a substantially forward direction to the adjacent depression. To carry the material laterally, a disproportionate distance would be to increase the amount of power needed by the cutter.

The ordinary single blade scraper that is used in prevailing types of road machines today, however, has the disadvantage that it moves against the road bed only as fast as the machine can move forwardly. By rotating the blade and thereby giving it a motion independent of the motion of the carriage structure of the machine, it may be moved against the roadway at a much faster rate than the forward travel of the machine and instead of forcing a single blade to its full depth of cut without any preliminary removal of material, the curved cross-section of the rotary cutter obtains a cut in which the depth varies from the forward edge of the cutter, where it is zero, to the rear extremity of the cut directly below the axis of the cutter where it is at its maximum.

A true planing effect is thus obtained, as contrasted with the scraping effect of the straight blade.

Another advantage over the straight blade 120 lies in the fact that a more slicing cut can be obtained by the blades which are set at an angle of forty-five degrees as compared with the usual angle of less than thirty degrees for a straight blade. The cut of the blades of my rotary cutter is a cross between a pure slicing cut and a strictly shear cut and is most efficient in loosening the surface of a hard-packed or gravelled road without producing too much friction therewith. In order to ob-

tain such a slicing shear with a straight blade, it would be necessary to employ a blade which would be prohibitively long in order to also cover the proper width of the cut.

5 Returning now to a consideration of the relation between lateral conveying and forward movement of the material, it will be seen that the angle of the blades is such that the tendency to throw the material forward will be as great, if not greater, than the tendency to convey it laterally. As a matter of fact, in actual practice, the tendency to throw the material forwardly is much greater than the lateral conveying tendency, for the reason that the 10 blades are rotating in a forward direction and all friction between the sharp, gravelled particles and the blade will result in a tendency to give the gravel particles a forward motion, whereas, in order to move laterally, they must 15 slide relative to the blade.

20 The combination of the tendency to throw material forwardly and of the tendency to convey it laterally, results in the following: Where a road bed is encountered with well-defined transverse ridges, the effect of the cutter is to throw the material forwardly from a ridge to the next adjacent depression; where a road is encountered in which the ridges run more longitudinally than transversely, the effect 25 will be mainly to throw the material laterally. This follows from the fact that the gravel will follow the course of least resistance and the rotating cutter exerts a push in both directions.

30 This effect differs from that of a straight blade in that in the straight blade, due to its much slower speed, there is a tendency for the gravel to pile up in front of the blade and where the gravel must move any considerable 35 distance from the point where it has been removed to the depression to be filled, its resistance to such movement will be so great that the blade will pass over it before it has reached the point of deposit.

40 The cutter is suspended from the frame of the vehicle by means of a carriage bar 23, to which is secured a pair of steel spring arms 24, pivoted upon a shaft 25. The arms 24 rigidly position the carriage bar 23 against 45 twisting from its proper horizontal position and serve also as draw bars. The weight of the carriage bar 23 is supported by adjustable mechanism including links 26, pivoted in eye bolts 27, which serve to partly secure the 50 arms 24 to the carriage bar, the upper ends of the links 26 being suspended from levers 28, secured to gears 29 upon stub shafts 30, journaled in bearings 31 and 32, supported upon the longitudinal members 10 and 15, respectively. The gears 29 mesh with pinions 33, 55 which are mounted on shafts 34, journaled in the same bearings 31 and 32 and provided with hand wheels 35. It will now be seen that by rotation of the hand wheels 35, the lever arms 28 may be raised or lowered to raise or

lower either end of the carriage bar 23. In thus raising or lowering the carriage bar, the twisting tendency produced will be compensated by the resiliency of the arms 24. The twisting tendency of the arms 24 themselves is 70 compensated by forming the openings 36 in the ends of the arms of hyperboloid cross-section, as shown in Fig. 6.

75 Power from an internal combustion engine or the like 37 is transmitted from a drive pinion 38 on the engine crank shaft to a bevel gear 39 on a shaft 40, which is mounted in a bracket 41, carried by the plate 42 which supports the engine 37. The plate 42 is supported between the auxiliary frame members 15. A 80 universal joint 43 connects the shaft 40 with an intermediate shaft 44, which is provided with an internally squared sleeve 45 to receive a squared shaft 46. The shaft 46 is in turn connected by means of a universal joint 47 to 85 a lower shaft 48, which is journaled in a bracket 49, mounted on the carriage bar 23. The lower end of the shaft 48 carries a bevel gear 50, which drives a bevel gear 51 on the shaft 19 of the cutter. The cutter shaft is 90 mounted in a bracket 49 and in a bracket 52, supported from the other end of the carriage bar 23.

95 It will now be seen that adjustment of the supporting mechanism vertically may be employed to tilt the cutter laterally, for instance, by raising one end of the cutter bar, that end of the cutter may be tilted upwardly. It will be understood, however, that the cutter will never be tilted any great extent, since 100 the machine is intended for maintaining roads in which the grade is already established.

105 Tilting of the cutter is taken care of by the universal connections 43 and 47 and the sliding connection of the shaft 46 with the sleeve 45 so that such tilting will not interfere with the drive from the engine.

110 It may be noted further that the suspension of the cutter is practically a floating suspension so that should any obstacles be encountered in the path of the cutter, which are of such nature that the cutter cannot remove them, it may ride over such obstacles.

115 Some changes may be made in the construction and arrangement of the parts of my invention without departing from the real spirit and purpose of my invention, and it is my intention to cover by my claims, any modified forms of structure or use of mechanical 120 equivalents, which may be reasonably included within their scope.

I claim as my invention:

125 1. In a road machine, a carriage having travel wheels, a cutter rotatably mounted in the carriage, said cutter comprising a plurality of helical blades mounted at an angle of between forty and sixty degrees to the cutter axis, and means for rotating the cutter in a direction opposite to the direction of rota- 130

tion of the travel wheels at a rate that is several times faster than the rate of revolution of the travel wheels during normal travel, the parts being so arranged that the cutter 5 will serve the three purposes of planing a road bed without leaving noticeable longitudinal ridges therein, of conveying material laterally, and of throwing material forwardly.

10. 2. In a road machine, a carriage having travel wheels, a cutter rotatably mounted in the carriage, said cutter comprising a plurality of helical blades mounted at an angle of between forty and sixty degrees to the cutter axis, and means for rotating the cutter in a direction opposite to the direction of rotation of the travel wheels at a rate of at least one revolution per second, the parts being so arranged that the cutter will serve the three 15 purposes of planing a road bed without leaving noticeable longitudinal ridges therein, of conveying material laterally, and of throwing material forwardly.

20. 3. In a road machine, a carriage having travel wheels, a cutter mounted in the carriage for rotation about an axis that is substantially at right angles to the direction of travel of the machine, said cutter comprising a plurality of helical blades mounted at an 25 angle of between forty and sixty degrees to

the cutter axis, and means for rotating the cutter in a direction opposite to the direction of rotation of the travel wheels at a rate of at least one revolution per second, the parts being so arranged that the cutter will serve the 35 three purposes of planing a road bed without leaving noticeable longitudinal ridges therein, of conveying material laterally, and of throwing material forwardly.

4. In a road machine, a carriage having travel wheels, a cutter mounted in the carriage for rotation about an axis that is substantially at right angles to the direction of travel of the machine, said cutter comprising at least four helical blades mounted at an 40 angle of between forty and sixty degrees to the cutter axis, and means for rotating the cutter in a direction opposite to the direction of rotation of the travel wheels at a rate of at least one revolution per second, the parts 45 being so arranged that the cutter will serve the three purposes of planing a road bed without leaving noticeable longitudinal ridges therein, of conveying material laterally, and of throwing material forwardly.

Signed this 27 day of July, 1927, in the county of Minnehaha and State of South Dakota.

DELBERT WHEELER.
